UNITED STATES PATENT OFFICE.

HENRY G. VOIGHT, OF NEW BRITAIN, CONNECTICUT, ASSIGNOR TO RUSSELL & ERWIN MANUFACTURING COMPANY, OF NEW BRITAIN, CONNECTICUT, A CORPORATION OF CONNECTICUT.

LOCK AND LATCH.

No. 892,336.

Specification of Letters Patent. Patented June 30, 1908.

Application filed April 3, 1908. Serial No. 424,874.

To all whom it may concern:

Be it known that I, HENRY G. VOIGHT, a citizen of the United States, residing at New Britain, county of Hartford, State of Connecticut, have invented certain new and useful Improvements in Locks and Latches, of which the following is a full, clear, and exact description.

My invention relates to improvements in locks and latches, particularly useful in connection with French windows and the like, in which it is desired to have both a latch bolt and means whereby the window or door may be securely locked. By my improvement I have combined in such a device both a latch and locking mechanism which is operable through the medium of a single operating device or handle.

I have shown the preferred form of my invention in the accompanying drawing, in which the single figure is a side elevation of such a lock, with the cover plate removed, the ends of the locking bolts being broken away and shortened.

25 In the drawing, 1 represents a face plate, 2 the lock case, 3 the latch bolt, 4—4 the dead bolts or locking bolts.

5 is the roll-back carrying two arms 5^a 5^a.

6 is the hub of a second roll-back, the same 30 being mounted to rotate independently of the roll-back 5.

6^a is the roll-back arm on hub 6.

7 is an abutment on the hub 6 standing in the path of one of the arms 5^a.

35 4^a 4^a are corresponding tails or slides on the dead bolts 4—4. Each of these slides is provided with a recess to receive the roll-back arms 5^a, and with the oppositely inclined shoulders at each side of said recess, 40 the same being designed to receive the ends of the roll-back arms 5^a to hold the bolts 4 extended or retracted. In the drawings, the bolts 4 and slides 4^a are shown in the retracted position.

45 3^a is a lever pivotally connected at one end to the tail of the latch bolt 3 and at its other end to the lock case 2, as indicated at 3^b. A spring 3^c normally swings the lever 3 in a direction to project the latch bolt 3.

50 8 is a spring arranged to frictionally coöperate with one of the arms 5^a to hold the roll-back in one position or the other. This spring is carried by one of the slides 4^a, while the hump on said spring, shown in the drawings, stands opposite the notch in said slide

whereby when the corresponding arm of the roll-back 5 rests on one side or the other of said hump it will be frictionally held against accidental displacement, the drawing showing the roll-back 5 being held against accidental displacement in that position in which the locking bolts 4 are retracted.

9 is a dogging device arranged to be operated by a key adapted to pass through the key-hole 10. In the adjacent slide 4^a of one 65 of the locking bolts, a suitable notch or notches are formed, as shown, to receive the dog 9, the function of said dog being to positively block the slides 4^a against movement. The slides, dog and various parts of the mechanism are supported in and by the lock case or front plate 1 thereof. In the particular form shown, the hub 6 is rotatably supported directly upon the hub of the roll-back 5, this being a convenient and economical construc- 70 75 tion.

11 is a stop shoulder in the lock case to the rear of the roll-back arm 6^a.

12 is a spring-pressed stud carried by the lock case and adapted to bear in notches in 80 the dog 9, said stud representing one convenient means for preventing the accidental displacement of the dog in either its dogging or non-dogging position. In the drawings the dog 9 is shown as retracted.

85 Operation: With the parts as shown in Fig. 1, if the roll-back 5 is rotated clockwise, it will have no effect upon the locking bolts 4—4, but it will engage the abutment 7 and rotate the roll-back hub 6 and arm 6^a in a 90 similar direction and so that said arm 6^a will engage the lever 3^a so as to withdraw the latch bolt 3. Upon releasing the hub 5, the spring 3^c will restore these parts to their normal position shown in the drawings. If it is 95 desired to lock the door, the user has but to rotate the hub 5 in a reverse direction, whereupon one of the arms 5^a will first repress spring 8. By that time both arms will have entered their corresponding notches in the 100 slides 4^a 4^a. And further, movement of the roll-back 5 will cause both of said arms 5^a to move the slides 4^a in a direction to project the locking bolts 4. This is continued until the arms 5^a stand in a position at right angles 105 to that indicated in the drawing, whereupon the bolts 4 will be fully projected and the arms 5^a will bear against the opposite inclines on the respective slides so as to hold the bolts projected. At this time if it is de- 110

sired to prevent any possibility of opening the door, the dogging device 9 may be projected, advancing the same into the uppermost of the two corresponding notches 5 shown at the inner edge of the adjacent slide 4^a, the spring-pressed stud 12 being pressed back during this movement of the dog 9. This reverse movement of the roll-back 5 does not disturb the position of the roll-back 10 6, since the arm 5^a, shown as adjacent to the abutment 7, moves in a direction away from the latter. Suitable keeper plates are, of course, employed to receive the locking bolts 4. In the preferred construction there 15 are two of such bolts employed.

What I claim is:

1. In a lock and latch mechanism, a latch bolt, a locking bolt, a roll-back for each, means for operating the roll-back adapted to 20 the latch bolt to control the latter, said latch bolt roll-back being controlled through the medium of the roll-back for the locking bolt.
2. In a lock and latch mechanism, a latch bolt, a locking bolt, two concentrically 25 mounted but independently, rotatable roll-backs, one for the locking bolt and one for the latch bolt, and means for operating the roll-back adapted to the latch bolt to control the latter, said means being dependent upon 30 the operation of the first mentioned roll-back.
3. In a lock and latch mechanism, a latch bolt, a locking bolt, a roll-back for each, one of said roll-backs being rotatable independently of the other, the other roll-back being 35 rotatable independently with the first.
4. In a lock and latch mechanism, a latch bolt, a locking bolt, a roll-back for each, said roll-backs being mounted one on the other but capable of independent rotation, means 40 for operatively connecting one of said roll-backs with the locking bolt, and means for operatively connecting the same roll-back with the second roll-back for operating the latch bolt.
- 45 5. In a lock and latch mechanism, a latch bolt, a locking bolt, a roll-back for each,

means for interlocking said roll-backs when one of them is rotated in one direction for operating the latch bolt, one of said roll-backs being operable independently of the other when rotated in a reverse direction to operate the locking bolt.

6. In a lock and latch mechanism, a spring-actuated latch bolt, a roll-back therefor, a locking bolt, a roll-back therefor, said last 55 mentioned roll-back being operable independently of the other, the other roll-back being operable through the medium of the first by the rotation of the same in one direction.

7. In a lock and latch mechanism, a latch bolt, a locking bolt, a roll-back for each, the latch bolt roll-back being rotatable and independently mounted on the locking bolt roll-back, and an abutment on the latch bolt roll-back arranged to be engaged by the locking bolt roll-back when the latter is rotated in one direction only whereby said roll-backs 60 may be coupled to operate the latch bolt.

8. In a lock and latch mechanism, a spring-pressed latch bolt, two oppositely arranged locking bolts, a two-armed roll-back adapted to advance and retract the locking bolts, another roll-back mounted thereon arranged to operate the latch bolt, and means to couple 65 said roll-backs when one of them is rotated in one direction, said roll-backs being uncoupled upon a reverse movement.

9. In a lock and latch mechanism, a lock bolt, a latch bolt, means for operating said 80 bolts independently including independent roll-backs, means for operating one of said roll-backs to move it in either direction, means to couple said roll-backs to move both simultaneously in one direction, and a dogging device co-operating with one of the aforesaid parts to hold said locking bolt against 85 movement.

HENRY G. VOIGHT.
